ATTORNEY.

UNITED STATES PATENT OFFICE.

JUSTIN KAY TOLES, OF SAN FRANCISCO, CALIFORNIA.

REVOLVING-ENDLESS-BAND OIL-BURNER.

1,078,972.

Specification of Letters Patent.

Patented Nov. 18, 1913.

Application filed January 31, 1913. Serial No. 745,494.

To all whom it may concern:

Be it known that I, JUSTIN KAY TOLES, a citizen of the United States of America, residing at San Francisco, in the county of San Francisco, State of California, have invented a certain new and useful Revolving-Endless-Band Oil-Burner; and I do hereby declare the following to be a full, clear, and exact description of the invention, such as will enable others skilled in the art to which it appertains to make and use the same.

This invention relates to revolving endless band oil burners, and it may be said to consist in the provision of the novel and advantageous features and in the novel and improved construction, arrangement and combination of parts as will be apparent from the description and claims which follow hereinafter.

One object of the invention is to provide a novel and improved oil burner in which a revolving endless band is adapted to carry and supply the oil in constant quantities for combustion in an effective manner.

Another object of the invention is to provide novel and improved means for easily regulating to the desired degree the size and shape of the flame to render it suitable either for heating, or cooking, or illuminating purposes.

A further object of the invention is to provide novel and improved means for supplying in an effective manner the proper amount of oil and air necessary for perfect combustion.

Further objects of the invention are to provide a novel and improved oil burner of the nature specified which is simple in character, cheap to manufacture, economical and effective in use, easy to adjust and regulate in operation, adapted to produce an intense heat when desired, and in which combustion is effected without smoke or odor or any burning or carbonizing of the endless band.

Other objects and the advantages of the invention will be apparent to those skilled in the art from a consideration of the preferred form of construction embodying the invention, taken in connection with the accompanying drawings, in which—

Figure 1 is a partly broken and sectional view of the oil burner; Fig. 2 is a partly broken and sectional view taken on the line 2—2 of Fig. 1; Fig. 3 is a partly broken and sectional view of a portion of the oil

burner taken on the line 3—3 of Fig. 1; and Fig. 4 is a partly broken and sectional view of a portion of the oil burner taken on the line 4—4 of Fig. 2.

60

The endless band 5, preferably of coarse or open texture, is made of absorbent material when light oils are to be burned and is made of woven wire fabric when heavy or viscous oils—which will adhere to the wire fabric—are to be burned. The endless band 5 passes around the drums 6 and 7 respectively mounted on the shafts 8 and 9 bearing in the sides 10 and 11 of a suitable casing formed to provide a reservoir 12 for oil 13 in the lower part thereof; the drum 7 being arranged near the bottom of the reservoir 12 and the drum 6 being arranged above the drum 7 outside of the reservoir 12. The revolution of the drums 6 and 7 and consequently of the endless band 5 may be effected by means of chains 14 which pass around sprocket wheels 15 mounted fast on the shafts 8 and 9—suitable spring motor mechanism indicated at 16 and adapted to be wound by 70 the handle 17 being operatively connected to the shaft 8.

The top of the reservoir 12 is preferably formed of upwardly converging walls 18 the adjacent ends of which are spaced from each other to provide an opening through which the endless band and the chains 14 pass into and out of the oil reservoir between vertical plates 20 which are arranged between the sides 10 and 11 and bear against vertical 85 extensions 19 on the adjacent end portions of the walls 18. The vertical plates 20 may be raised or lowered at will to uncover any desired amount of the endless band 5 on the drum 6 to regulate the supply of oil to the 90 flame, and they may be locked in adjusted position by ears 21 thereon having slots 22 in which are disposed clamping pins 23 adapted to screw into the sides 10 and 11.

To regulate the size and shape of the 100 flame, wing-plates 24 are slidably mounted in guideways 25 on the sides 10 and 11 to admit of adjacent ends of the wing-plates being spaced apart to the desired extent at the top of the endless band 5. The remote 105 ends of the wing-plates 24 may have thereon hinged gates 26—held in adjusted position by springs 27 thereon bearing against the sides 10 and 11—for regulating the supply of air passing between the wing-plates and 110 the walls 18 to the burner.

Air for supporting combustion may be

supplied through the endless band 5 by means of a chamber 28 arranged in the interior of the endless band and having the upper end thereof disposed adjacent to 5 openings 29 in the drum 6; the lower end portion of the chamber 28 being in communication with openings 30 in the sides 10 and 11. Doors 31 may be slidably mounted on the sides 10 and 11 for adjusting the amount 10 of air passing through the openings 30.

The walls 32 for inclosing the flame of the oil burner extends upwardly on the sides 10 and 11 and may be of suitable transparent material when the oil burner is used for 15 illuminating purposes.

The heated air supply chamber 33, preferably having the lower and upper sides 34 and 35 thereof arc-shaped, may be suitably affixed on the wall 32 and arranged adjacent to the top of the endless band 5 and preferably provided centrally on the lower side 35 with an upwardly diverging plate 36 for deflecting the gases and flames toward the opposite end walls 37 and 38 of 20 the chamber 33. Air passes into the chamber 33 through openings 39 in communication with the openings 40 in the wall 32 and after being heated passes out of the chamber 33 through openings 41 in the end walls 25 37 and 38 and effectually mixes with the gasified oil to completely burn the same in a clean manner without odor or smoke or deposit of soot on the parts.

When the oil burner is used for heating 30 or cooking purposes, the flame inclosing wall 32 may be provided with a suitable top cover 42 provided with openings 43 there-through.

While one form of construction embodying the invention has been particularly illustrated and described there are many changes and modifications thereof that will readily occur to those skilled in the art, wherefore the right is reserved to all such 40 changes and modifications as do not depart from the spirit and scope of the invention as defined in the appended claims.

I claim:

1. The combination of an oil reservoir, 50 said reservoir provided with an opening, substantially vertical plates arranged at said opening, an endless band arranged between the plates and adapted to pass through the opening in the reservoir, means 55 adapted to supply air for combustion through the endless band, and means including a motor operatively connected with said endless band and adapted to revolve the same.

60 2. The combination of an oil reservoir, said reservoir provided with an opening, substantially vertical plates arranged at said opening, an endless band arranged between the plates and adapted to pass 65 through the opening in the reservoir, means

adapted to supply air for combustion through the endless band, means operatively connected with the endless band and adapted to revolve the same, and a heated air supply chamber arranged adjacent to the top 70 part of the endless band.

3. The combination of a casing, an oil reservoir therein, said reservoir provided with an opening, substantially vertical plates arranged between the sides of said 75 casing, an endless band arranged between the vertical plates and adapted to pass through the opening in the reservoir, means operatively connected with the endless band and adapted to revolve the same, a heated air supply chamber arranged adjacent to the top of the endless band, and wing-plates 80 adjustably mounted on the sides of the casing, substantially as set forth.

4. The combination of a casing, an oil reservoir therein, said reservoir provided with an opening, substantially vertical plates arranged between the sides of said casing, an endless band arranged between the vertical plates and adapted to pass 85 through the opening in the reservoir, means operatively connected with the endless band and adapted to revolve the same, and wing-plates adjustably mounted on the sides of the casing, substantially as set forth.

5. The combination of a casing, an oil reservoir therein, said reservoir provided with an opening, adjustable substantially vertical plates arranged between the sides of said casing, an endless band arranged between the vertical plates and adapted to pass 90 through the opening in the reservoir, means operatively connected with the endless band and adapted to revolve the same, and wing-plates adjustably mounted on the sides of the casing, substantially as set forth.

6. The combination of a casing, an oil reservoir therein, said reservoir provided with an opening, substantially vertical plates arranged between the sides of said casing, an endless band arranged between the vertical plates and adapted to pass 110 through the opening in the reservoir, means operatively connected with the endless band and adapted to revolve the same, and means adapted to supply air for combustion 115 through the endless band.

7. The combination of a casing, an oil reservoir therein, said reservoir provided with an opening, substantially vertical plates arranged between the sides of said casing, an endless band arranged between 120 said vertical plates and adapted to pass through the opening in the reservoir, means operatively connected with the endless band and adapted to revolve the same, a heated air supply chamber arranged adjacent to 125 130

- the top of the endless band, wing-plates adjustably mounted on the sides of the casing, and means adapted to supply air for combustion through the endless band.
- 5 8. The combination of a casing, an oil reservoir therein, said reservoir provided with an opening, adjustable substantially vertical plates arranged between the sides of said casing, an endless band arranged between the vertical plates and adapted to pass through the opening in the reservoir, means operatively connected with the endless band and adapted to revolve the same, a heated air supply chamber arranged adjacent to the top of the endless band, means adapted to supply air for combustion through the endless band, wing-plates adjustably mounted on the sides of the casing, and hinged gates on the wing-plates, substantially as set forth.
- 10 9. The combination of an oil reservoir provided with an opening, substantially vertical plates arranged at said opening, an endless band arranged between the plates and adapted to pass through said opening 25 in the reservoir, and means adapted to supply air for combustion through said endless band.
- 15 10. The combination of an oil reservoir provided with an opening, substantially vertical plates arranged at said opening, an endless band arranged between the plates and adapted to pass through said opening in the reservoir, a flame inclosing wall arranged above the reservoir, and a heated air supply chamber provided with openings therein and arranged within and affixed on said inclosing wall above the top of the endless band.
- 20 In testimony whereof, I have signed my name to this specification in the presence of two subscribing witnesses at San Francisco, county of San Francisco, State of California, this 23rd day of January A. D. 1913.
- JUSTIN KAY TOLES.
